UNITED STATES PATENT OFFICE.

ISAAC W. JOHNSON, OF NEW RICHMOND, WISCONSIN.

MORTISING-MACHINE.

SPECIFICATION forming part of Letters Patent No. 286,016, dated October 2, 1883.

Application filed July 25, 1883. (No model.)

To all whom it may concern:

Be it known that I, I. W. JOHNSON, a citizen of the United States, residing at New Richmond, in the county of St. Croix and State of Wisconsin, have invented certain new and useful Improvements in Mortising-Machines; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a plan view. Fig. 2 is a vertical section. Fig. 3 is a cross-section, and Fig. 4 is a detail view.

This invention has relation to mortising-machines; and it consists in the construction 20 and novel arrangement of parts, as will be hereinafter fully described, and particularly pointed out in the claims appended.

Referring by letter to the accompanying drawings, *a a* designate the bed-rails of the 25 frame of the machine, which are mounted on rollers *b*, and are mortised through laterally near each end, at *c*, to receive the graduated ends of the cross-rails *d* and *e*, on which they are laterally adjustable, being held to their 30 adjustments by set-screws *f*, passing down through them into the graduated ends of the cross-rails *d e*. This lateral adjustment of the bed-frame is provided in order that the machine may be fitted to timbers of different 35 widths, hooked clamp-rods *g*, having thumb-nuts at their upper ends, passing through vertical apertures *g'* in the bed-rails *a a*, being provided for clamping the machine in place upon the timber. Projecting arms *h*, extending 40 parallel with the graduated portions of the cross-rails *d* and *e*, are secured in the inner ends of the lateral mortises *c* by pins *c'*, driven down through the bed-rails into their inner ends. Their inner ends are provided with vertical apertures, which register with the apertures *g'* in the bed-rails *a a*, and their outer 45 ends are provided with vertical apertures *g''*, for the reception of the clamp-rods *g* when they are removed from the apertures *g'*.

50 *h h'* designate the bed-rails of the chisel-carrying frame, which are mortised laterally

through near each end to receive the reduced ends *h²* of the side rails, *i i*, of the chisel-carrying frame *o*, so that this frame may be adjusted with the bed-rails *a a*, the bed-rails *h h'* being secured upon the upper faces of the bed-rails *a a* by the encircling straps *k*, which permits the chisel-carrying frame *o* to have a longitudinal movement back and forth on the bed-rails *a a*. Set-screws *l* are employed to 60 hold the rails of the carrying-frame to their adjustments. A rack-bar, *m*, extends from the side of the carrying-frame *o* into and through a guide-recess, *n*, in a vertical wall, *p*, rising from the cross-rail *e*, and engages a cog-wheel, *q*, *p*, having bearings in boxes on the top of the vertical wall *p* and working in the guide-recess *n*. This cog-wheel *q* is provided with a crank-handle, *q'*, by turning which the chisel-carrying frame *o* is moved back and forth on 70 the bed-rails.

r designates a hinged fulcrum for the lever *r'*, which is pivoted in the bifurcated upper end of the hinged fulcrum. The lower end of this fulcrum is also bifurcated to receive the 75 eye of a screw *s*, through which the connecting-pivot *s'* is passed to form the hinge. This screw *s'* is driven into the bed-rail *h* of the carrying-frame *o*, so that by unscrewing it at any time the lever *r r'* may be removed. 80

t designates a bar or plate having slotted ends *t'* and a central block portion, *t*, which is recessed vertically in the form of a cross having arms of equal length, and in this recess is fitted a guide-tube, *u*, conforming in shape in 85 cross-section to the cross-form recess *u'*. This plate is secured to the bed-rails *h h'* by set-screws *v*, so that it is adjustable thereon and removable therefrom.

w designates the chisel, which is adjustable 90 in a rotary direction on an eye-screw, *w'*, hinged to a clamp, *x*, adjustable on the lever *r'*. The chisel *w* works in the guide-tube *u* when mortises are being cut, and either end mortises or side mortises may be cut in the 95 timber by turning the chisel on its screw, first withdrawing it from the guide-tube.

z designates a block recessed vertically at its center for the reception of a rectangular guide-tube, *z'*, and mortised laterally near each end 100 for the reception of the reduced ends of the side rails, *i i*, of the chisel-carrying frame *o*,

set-screws z^2 being employed to hold it in place on said side rails.

This device is to be used in preparing boxing, at which time the plate t should be removed from the machine. The clamp-rods nearest this block should be removed and placed in the vertical apertures g^2 of the projecting arms h^2 , and the chisel should be adjusted on the lever r , so that it can be worked 10 in the rectangular guide-tube z' , when the machine may be clamped on the board and the recesses cut. When mortising is being done, the block z should be removed.

A full-sized machine of this construction is 15 only twenty-five inches long, and as all of its parts are held together by set-screws, it may be readily and quickly taken apart and packed in an ordinary tool-chest when not in use, or when it is desired to transport it.

Having thus fully described my invention, what I claim as new, and desire to secure by Letters Patent, is—

1. The combination, with the laterally-ad-

justable bed-rails $a a$ on the graduated cross-rails d and e , set-screws f , and clamp-rods g , 25 of the adjustable chisel-carrying frame o , strapped to the bed-rails $a a$, the adjustable removable plate t , provided with the cross-form guide-tube u , the removably hinged lever $r r'$, the adjustable chisel w on the lever r , and 30 the rack-bar and cog-wheel for operating the carrying-frame o , substantially as specified.

2. The block z , recessed vertically at its center to receive the guide-tube z' , and mortised laterally near each end to receive the reduced ends of the side rails of the carrying-frame o , in combination with the bed-frame and carrying-frame, the hinged lever, the chisel, and the rack-bar and cog-wheel, substantially as specified. 35

In testimony whereof I affix my signature in presence of two witnesses.

ISAAC W. JOHNSON.
